UNITED STATES PATENT OFFICE.

JOHN C. GOULD, OF CHICAGO, ILLINOIS.

NAIL-PLATE FEEDER.

SPECIFICATION forming part of Letters Patent No. 317,529, dated May 12, 1885.

Application filed January 27, 1885. (No model.)

To all whom it may concern:

Be it known that I, JOHN C. GOULD, a citizen of the United States, residing in Chicago, in the county of Cook and State of Illinois, 5 have invented a new and useful Improvement in Nail-Plate Feeders, of which the following is a specification.

This invention relates to the grippers used in nail-plate feeders for gripping and feeding 10 forward the nail-plate rod; and it consists in the novel features hereinafter specified.

In the drawings accompanying this specification and forming a part thereof, Figure 1 is a plan view of my present invention. Fig. 2 15 is a bottom view. Fig. 3 is an end view, partly in section. Fig. 4 is a side elevation. Fig. 5 is a central vertical longitudinal section; and Fig. 6 is an elevation of the grippers, showing the other side thereof from that 20 given in Fig. 3. This latter view is also partly in section.

In said drawings, A represents the bracket whereby the grippers are supported.

B B' are the grippers acting upon the plate-rod and actuating it intermittently toward the 25 knives. They are supported upon a pivot, b, held between two conically-pointed set-screws, b', and are swung upon this pivot by the push-rod C, in the usual manner.

D is the set-screw by which the back-throw 30 of the grippers is limited, said set-screw being secured in the bracket or yoke attached thereto and passing through the arm H projecting from the gripper B. Between the grippers is 35 an intermediate piece E, similar in most respects to that shown in my patent of January 22, 1884. This piece is supported upon a pin, e, projecting from the gripper B'. It loosely encircles both the bolt n (which limits the spread 40 of the grippers) and the pivot b, and its upper end forms the support for the plate-rod, as in said patent. At its lower end it receives the push-rod, and hence forms the medium for 45 both oscillating the grippers on their pivot and for actuating them to grip the plate-rod.

In the gripping function I devolve all the movement upon the gripper B', the other gripper, B, being held stationary upon the pivot b by the set-screw o; hence the gripper 50 B' encircles the pivot loosely, as shown.

To cause the spreading of the lower ends of the grippers, and the gripping by their upper

ends when the push-rod acts upon the intermediate piece E, I provide said intermediate piece with a roller, r, which works upon a vertical surface, p, formed upon the lower end of gripper B, and inclined relative to the line of the feed. This crowds the intermediate piece and the gripper B' in a lateral direction and causes the upper ends of the grippers to seize 60 the plate-rod, the gripper B' being furnished with a straight bearing-surface, p', against which a like surface, p'', on the intermediate piece bears.

At either end of the angling surface p are 65 curved guards p'', which serve to confine and limit the movement of the roller, and at the back of the intermediate piece are guards p', which act as stops to the forward movement of the intermediate piece.

The gripping-surfaces proper of the grippers I form of rotatable vertical disks F, mounted upon horizontal pivots f, frictionally held in the upper ends of the grippers, the amount of friction being capable of regulation by the set-screws f'. When the grippers swing forward, these disks, which are then in gripping contact with the plate-rod, turn upon their pivots a fraction of a revolution with each impulse, and consequently, 75 when the grippers next seize the rod, the disks are in a slightly changed position. This slight rotation occurs at each operation, and consequently the wearing of grooves in the gripping-surface is prevented, the disks wearing evenly throughout, and thus obviating the necessity of frequent renewals of these surfaces. If the grippers should not work truly in line with the other parts of the machine—that is, should tend to deflect the plate-rod to 80 one side—I provide means for correcting the evil by making the supporting-yoke A', in which they are pivoted separate from and adjustable upon the bracket A, instead of in one piece therewith, according to the former construction, the dividing-line between the two being a circular one with the gripping-point as a center. The yoke is held to the bracket by the bolt a' and washer a'', the opening in the yoke through which the bolt passes being laterally enlarged, as indicated by dotted lines 85 in Fig. 1. By this means the yoke may be so adjusted upon the bracket as to bring the gripping-surfaces into true alignment. The

spring *s* holds the push-rod and intermediate piece together, as in my former patent.

By making pin *e* hollow I am enabled to utilize it as a holder for the spring *g*, whereby the gripping-surfaces are forced apart after each operation.

I claim—

1. The combination, in a nail-plate feeder, of gripper *B'*, having hollow pin *e*, with the opposing gripper, *B*, and the spring *g*, held in said pin and acting to spread the grippers, substantially as specified.

2. In a nail-plate feeder, the gripper *B*, provided with the angling surface *p*, but having no lateral movement, the intermediate piece actuated by the push-rod and carrying the roller *r*, working upon said surface *p*, and the laterally-moving gripper *B'*, all combined and operating substantially as specified.

3. In combination in a nail-plate feeder, the gripper *B*, having the inclined surface *p* and guards *p*³, with the intermediate piece *E*, provided with roller *r*, bearing upon said inclined surface, substantially as specified.

4. In a nail-plate feeder, the combination, with the grippers, of the gripping-surfaces composed of rotatable vertical disks, substantially as specified.

5. In a nail-plate feeder, the combination, with the grippers, of the supporting bracket and yoke when the latter are made separate from each other and adjustably secured together, substantially as specified.

JOHN C. GOULD.
